W. F. HARRINGTON

SHAFT SUPPORT

Filed July 26, 1917

Inventor
William F. Harrington

By *Chester H. Braselton*
Attorney

UNITED STATES PATENT OFFICE.

WILLIAM F. HARRINGTON, OF TOLEDO, OHIO, ASSIGNOR TO THE WILLYS-OVERLAND COMPANY, OF TOLEDO, OHIO, A CORPORATION OF OHIO.

SHAFT SUPPORT.

Application filed July 26, 1917. Serial No. 182,863.

To all whom it may concern:

Be it known that I, WILLIAM F. HARRINGTON, a subject of the King of Great Britain and Ireland, residing at Toledo, in the county of Lucas and State of Ohio, have invented certain new and useful Improvements in Shaft Supports, of which I declare the following to be a full, clear, and exact description.

10 This invention relates to improvements in shaft supports and particularly to improvements in the mounting for the fan shaft of an internal combustion engine.

15 The object of my invention is to provide an improved fan shaft mounting for automobile engines, which is automatically adjustable to keep the fan belt tight.

20 A further object of my invention is to provide an improved mounting for the fan shaft of an internal combustion engine, which mounting will permit of the vertical movement of the fan shaft, but will prevent swinging of the same from side to side.

25 A further object of my invention is to provide a fan shaft mounting, which is automatically adjustable to tighten the belt, and which is provided with improved means for lubricating the same.

30 A further object of my invention is to provide an improved mounting for a fan shaft, which is simple in construction and can be quickly and readily manufactured and assembled.

35 Further objects, and objects relating to economies of manufacture and details of construction, will definitely appear from the detailed description to follow.

40 I accomplish the objects of my invention by the devices and means described in the following specification. My invention is clearly defined and pointed out in the appended claims.

45 A structure constituting a preferred embodiment of my invention is illustrated in the accompanying drawing, forming a part of this specification, in which—

Figure I is a view in side elevation of

an internal combustion engine, having a fan shaft mounted in accordance with my 50 invention, a part of said mounting being shown in section in order to show the construction more clearly.

Figure II is an enlarged, detail, fragmentary view, partly in section, showing 55 the fan shaft mounting in greater detail.

Figure III is a detail, fragmentary, sectional view taken substantially on the line III—III of Figure II and Figure IV is a fragmentary, detail view taken substantially on the line IV—IV of Figure III.

60 In the drawings, similar reference numerals refer to similar parts throughout the several views, and the sectional views are taken looking in the direction of the little arrows at the ends of the section lines.

Considering the numbered parts of the drawings, the internal combustion engine 10 drives the shaft 11 on which the pulley 70 12 is mounted. An arm 13 extends upwardly from the head of said engine and is provided with a vertical passage 14 therein, in which the post 16 is slidably mounted, and said arm also has a vertical face 75 15 below the portion in which the passage 14 is provided. The shaft 17 extends horizontally from the lower end of the vertical post 16, in one direction, and in the opposite direction from said post, there is 80 provided the head 18 having a vertical face which is adapted to engage with and slide up and down on the vertical face 15 of the arm 13. The horizontal passage 20 is provided in the shaft 17, being closed at one 85 end by the plug 19, and connects with the passage 21 in the post 16, as clearly appears from Figure II of the drawing.

90 Compression spring 22 is provided on the post 16, between the arm 13 and the head 23 on said post, so as to normally force the post upward in the passage 14 in said arm. An oil cup 24 is carried on the upper end of said post, and lubricant feeds through the passage 21 and the passage 20 95 and through an opening provided in the

sleeve 25, which is fixed on the shaft 17, so as to lubricate the pulley 26, which is journaled on said sleeve 25. The sleeve 25 is held on the shaft by means of the nut 3 27 threaded on the end of said shaft and said pulley 26 is provided with a rearwardly extending sleeve 28, having an annular flange 29, to which the fan blades 30 are secured in a suitable manner. The pulleys 10 12 and 26 are connected by the fan belt 31, so that the fan is driven by said belt from the shaft 11.

From the description of the parts given above, the operation of my device should 15 be very readily understood. The shaft 17, upon which the fan is journaled, is subject to vertical movement, due to the fact that the post 16, which is part of said shaft, is vertically movable in the passage 14 in 20 the arm 13, and the spring 22 tends to hold the shaft in the uppermost position so that the belt 31 connecting the pulleys 26 and 12 is always kept tight. The engagement of the face 18 on the head provided on the 25 end of the shaft 17 with the vertical face 15 on the arm 13 keeps the shaft from twisting from one side to the other, and insures a broad bearing surface for the end thereof, so that it is compelled to move 30 vertically and cannot twist or turn in the horizontal plane. The spring 22 allows a downward movement of the post 16 and the shaft so as to permit the easy removal of the fan belt whenever that is desired, and, as has been stated above, the spring 35 22 always keeps the fan belt tight and prevents its becoming slack, so as to prevent any trouble or annoyance on that account.

I am aware that the particular embodiment of my invention which I have here shown and described, is susceptible of considerable variation without departing from the spirit of my invention, but I have found that this particular embodiment is desirable 40 from many standpoints, and, therefore, I desire to claim the same specifically as well as broadly, as indicated by the appended claims.

Having thus described my invention, what 50 I claim as new and desire to secure by Letters Patent is—

1. In an internal combustion engine, the combination of an engine shaft; a pulley mounted thereon; an arm extending upwardly from the head of said engine, and having a vertical passage therein and a vertical face; a shaft having a vertical post 55 slidably mounted in said passage and a head slidably engaging said vertical face; a compression spring surrounding the upper end of said post, and exerting an upwardly directed pressure thereon; a pulley journaled on said shaft and having a laterally extending sleeve provided with an annular flange; fan blades secured to said flange; a belt con-

necting said pulleys; a lubricating cup on the upper end of said post; and a passage in said post and shaft for conducting lubricant to the pulley bearings.

2. In an internal combustion engine, the 70 combination of an engine shaft; a pulley mounted thereon; an arm extending upwardly from the head of said engine, and having a vertical passage therein and a vertical face; a shaft having a vertical post 75 slidably mounted in said passage and a head slidably engaging said vertical face; a compression spring surrounding the upper end of said post, and exerting an upwardly directed pressure thereon; a pulley journaled on said shaft and having a laterally extending sleeve provided with an annular flange; fan blades secured to said flange; and a belt connecting said pulleys.

3. In an internal combustion engine, the 80 combination of the engine shaft; a pulley mounted thereon; an arm extending upwardly from the head of said engine and having a vertical passage therein, and a vertical face; a shaft having a vertical post 85 slidably mounted in said passage, and a head slidably engaging said vertical face; a compression spring surrounding the upper end of said post, and exerting an upwardly directed pressure thereon; a pulley journaled 90 on said shaft; a fan mounted to turn with said pulley; and a belt connecting said pulleys.

4. In an internal combustion engine, the 95 combination of an engine shaft; a pulley mounted thereon; an arm extending upwardly from the head of said engine and having a vertical passage therein, and a vertical face; a shaft having a vertical post 100 slidably mounted in said passage and a head slidably engaging said vertical face; a pulley journaled on said shaft; a fan mounted to turn with said pulley; and driving connections between said pulleys.

5. In an internal combustion engine, the 105 combination of an engine shaft; a pulley mounted thereon; an arm extending upwardly from the head of said engine, and having a vertical passage therein; a shaft having a vertical post 110 slidably mounted in said passage; means for preventing the movement of said shaft in a horizontal plane; a pulley journaled on said shaft; a fan mounted to turn with said pulley; and driving connections between said pulleys.

6. In an internal combustion engine, the 115 combination of an engine shaft; a pulley mounted thereon; an arm extending upwardly from the head of said engine and having a vertical passage therein; a shaft having a vertical post 120 slidably mounted in said passage; a compression spring surrounding the upper end of said post and exerting an upwardly directed pressure thereon; a pulley journaled on said shaft; a fan 125

mounted to turn with said pulley; and driving connections between said pulleys.

7. In a device of the class described, the combination of a support; a shaft, having a post slidably mounted in said support and having a head slidably engaging a vertical face provided on said support; a compression spring surrounding the upper end of said post and exerting an upwardly directed pressure thereon; a pulley journaled on said shaft, and having a laterally extending sleeve provided with an annular flange; a fan secured to said flange; and means for driving said pulley.

15 8. In a device of the class described, the combination of a support having a vertical passage therein and a vertical face; a shaft having a vertical post slidably mounted in said passage and a head slidably engaging said vertical face; a pulley journaled on said shaft and having a laterally extending sleeve provided with an annular flange; a fan secured to said flange; and means for driving said pulley.

25 9. In a device of the class described, the combination of a support; a shaft having a post slidably mounted for vertical movement therein; a compression spring surrounding the upper end of said post, and exerting an upwardly directed pressure thereon; a pulley journaled on said shaft; a fan mounted to turn with said pulley; and means for driving said pulley.

30 10. In a device of the class described, the combination of a support; a shaft having a vertical post slidably mounted for vertical movement in said support; a compression spring surrounding the upper end of said post, and exerting an upwardly directed pressure thereon; means for preventing movement of said shaft in a horizontal plane; a pulley journaled on said shaft; and means for driving said pulley.

40 11. In a device of the class described, the combination of a support; a shaft having a post slidably mounted in said support for vertical movement therein; means for preventing movement of said shaft in a horizontal plane; a pulley journaled on said shaft; and means for driving said pulley.

45 12. In a shaft mounting, a support provided with a passage therein, a shaft provided with an angularly extending portion slidably mounted in said passage, and means for resiliently maintaining the shaft in position relative to the support.

50 13. In a shaft mounting, a support provided with a passage formed therein, a shaft having a post thereon slidably mounted in said passage, means for resiliently supporting the shaft, and means for preventing rotation of the post relative to the support.

55 14. In a shaft mounting, a support provided with a passage therein, a horizontal shaft provided with an angularly extend-

ing post directly upwardly from one end of the shaft adapted to be slidably mounted in said passage, and means surrounding a portion of said post for resiliently maintaining said post in position relative to said support.

70 15. In a device of the class described, the combination of a support, a shaft having a post slidably mounted in said support and having a head slidably engaging a vertical face provided on said support, and a coiled spring surrounding the upper end of said post and exerting an upwardly directed pressure thereon to resiliently support said shaft.

75 16. In an internal combustion engine, the combination of an engine shaft, a pulley mounted thereon, an arm extending upwardly from the head of said engine and having a vertical passage therein, a shaft having a vertical post extending upwardly from one end of the shaft and slidably mounted in said passage, a coiled spring surrounding the upper end of said post and exerting an upwardly directed pressure thereon, a pulley journaled on said shaft, and driving connections between said pulleys.

80 17. In an internal combustion engine, the combination of an engine shaft, a pulley mounted thereon, an arm extending upwardly from the head of said engine and having a vertical passage therein and a vertical face, a shaft having a post slidably mounted in said passage, and a head slidably engaging said face, a pulley mounted on said shaft, and driving connections between said pulleys.

85 18. In an internal combustion engine, the combination of an engine shaft, a pulley mounted thereon, an arm extending upwardly from the head of said engine and having a vertical passage therein, a shaft having an integral post slidably mounted in said passage, the opposite end of the shaft being free, means for preventing the movement of said shaft in a horizontal plane, a pulley journaled on said shaft, and driving connections between said pulleys.

90 19. In a device of the class described, the combination of a support having a vertical passage therein and a vertical face, a shaft having a post fixed thereto slidably mounted in said passage and a head slidably engaging said face, the shaft extending horizontally and being free at its opposite end, a pulley journaled on said shaft, and means for driving said pulley.

95 20. In a device of the class described, the combination of a support, a shaft having a post fixed thereto slidably mounted for vertical movement in said support, said shaft being free at its end opposite the post, a coiled spring surrounding the upper end of said post and exerting an upwardly directed

pressure thereon, a pulley journaled on said shaft, and means for driving said pulley.

21. In a device of the class described, the combination of a support, a shaft free at one end and having a vertical post fixed to the opposite end, said post being slidably mounted for vertical movement in said sup-

port, a coiled spring surrounding the upper end of said post and exerting an upwardly directed pressure thereon, and means for preventing movement of said shaft in a horizontal plane. 10

In testimony whereof I affix my signature.

WILLIAM F. HARRINGTON.
